BEVERAGE BREWER

Milton Immermann, River Road, Piermont, N.Y.; Robert H. Ensign, 8 Custer Place, Bronxville, N.Y.; Charles W. Fromm, 726 Delavan St., Teaneck, N.J.; and Gifford Jackson, 400 E. 57th St., New York, N.Y.

Filed Mar. 19, 1964, Ser. No. 79,084

Term of patent 14 years

(Cl. D2—3)

FIG. 2

FIG. 1

FIG. 4

FIG. 3

FIG. 1 is a front perspective view of a beverage brewer, showing our new design;

FIG. 2 is a side perspective view thereof;

FIG. 3 is a plan view thereof slightly in perspective; and

FIG. 4 is a perspective view of the side thereof opposite to the side shown in FIG. 2.

The rear of the beverage brewer is substantially plain in appearance.

We claim:

The ornamental design for a beverage brewer, as shown and described.
